COMBINED RAILING AND END COLUMN

Sherman Shore, Pittsburgh, Pa., assignor to Napco, Inc.,
Pittsburgh, Pa., a corporation of Pennsylvania

Filed Feb. 23, 1965, Ser. No. 83,927

Term of patent 14 years

(Cl. D13—7)

FIG. 1 is an elevational view of a combined railing and end column embodying the new design;

FIG. 2 is a cross-sectional view taken along line 2—2 of FIG. 1; and

FIG. 3 is a cross-sectional view taken on line 3—3 of FIG. 1 through the column showing the decorative panel insert.

The broken lines in the column and railing in FIG. 1 indicate that both components are of indeterminant length.

I claim:

The ornamental design for a combined railing and end column, as shown and described.
